GRINDING MACHINE

Everard Stubbs, Springfield, Vt., assignor to
Norton Company, Worcester, Mass., a corpora-
tion of Massachusetts

Application May 19, 1932, Serial No. 612,233

16 Claims. (Cl. 125—11)

This invention relates to grinding machines and more particularly to machines adapted to grind work pieces of irregular contour.

Heretofore in the grinding machines utilized to produce non-circular shapes, such as cams, it has been the practice to employ a grinding wheel of a cylindrical shape; and in order that the periphery of the wheel may engage the work throughout the entire surface as it rotates, the work head support has been arranged to move back and forth towards the center of the grinding wheel as the work rotates. Such machines are unsatisfactory due to their complicated construction necessitating a complex movement through which the work must be cyclically moved during the grinding operation, as well as to the fact that the grinding wheel may be used only within certain narrow limits of diameter if satisfactory grinding results are to be obtained. Great difficulty has been encountered in producing certain types of non-circular work, such as the familiar types of spline shafts by employing mechanisms as heretofore proposed.

As result of my experimentation, I have found it practicable to grind work pieces of irregular contour by a method which does not require any relative oscillation between the work and the wheel, but which depends on specially shaping the grinding wheels and rotating the wheel and work in synchronism at such angular rates during grinding that the wheel and work remain in proper grinding phase relation at all times.

It is the primary object of my invention to provide such a grinding machine in which the grinding wheel is of irregular contour and in which it may be readily trued to the desired shape and cutting condition so that work pieces of various contours may be correctly and efficiently ground.

A further object is to provide a truing mechanism which will pre-shape the grinding wheel to the exact contour required for grinding a work piece of irregular or eccentrically mounted cylindrical contour, and in particular to coordinate the parts of such a truing mechanism with the grinding wheel and work rotating mechanism that the wheel may be readily trued without removal from the machine.

With these and other objects in view as will be apparent to one skilled in the art, my invention resides in the combination of parts and the steps of a method set forth in the following description and the appended claims.

In the drawings illustrated, a grinding machine embodying this invention:

Fig. 1 is an end elevation of a grinding machine

showing the drive for the wheel and the work;

Fig. 2 is a fragmentary view showing the relation of the grinding wheel, work blank and forming attachment for truing the wheel;

Fig. 3 is a fragmentary view showing the mechanism for forming or truing the wheel;

Fig. 4 is a fragmentary cross sectional view of the forming mechanism taken approximately on line 4—4 of Fig. 3;

Fig. 5 is a sectional view taken along line 5—5 of Fig. 1 showing this invention as adapted for grinding a plurality of work blanks simultaneously; and

Fig. 6 is a diagrammatic view showing the relation of the wheel and the work in various angular positions during the grinding operation.

In accordance with my invention, I have provided a grinding machine wherein the grinding wheel is given a particular shape that is the conjugate of the desired work contour, such as a cam or an eccentrically mounted cylindrical work piece. The wheel and the work are rotated in a definite angular timed relation, but at different linear speeds at the point of grinding contact so that a given portion of the wheel will always contact with a given portion of the work. In other words, a grinding wheel is conjugate to an irregular work piece in the sense of this invention when the cutting portion of the wheel projects or recedes in complement to the receding or projecting parts of the work with which said cutting parts contact and the wheel and work rotate in substantially continuous contact but at different linear speeds. In a machine of this type, certain fixed points in the work and the wheel are withheld from recession or movement towards or from the work axis during the grinding operation, the only movement thereof being the feeding action required to grind the work to the desired extent. In other words, if the operative faces of the grinding wheel and the work are their peripheries, then their axes are fixed and the sum of the radii of the work and the wheel at the point of grinding contact always remains constant except as the grinding wheel is fed toward the work axis to reduce the work to the required size. If the side face of either wheel or work is utilized, then one may consider a fixed plane therein perpendicular to the axis of rotation as the position from which measurement is made.

One form of my machine which embodies this principle, has the grinding wheel and the work arranged to rotate in angular synchronism about relatively fixed parallel axes with their periph-

eries in operative contact, the wheel and work being relatively movable towards each other so that the wheel may be fed into the work to grind it to the desired size. It should be noted, however, that the shape or contour of the work is controlled wholly by the shape of the grinding wheel and not by the infeed thereof, as is the case in the standard type of cam grinding machine now on the market. The work and the wheel are rotated in angular synchronism, either at the same number of revolutions per minute or with the wheel rotating at a definite angular rate which is a multiple of the angular rate of the work rotation.

15 The grinding wheel may be given its required grinding shape by a truing tool which is moved towards and from the wheel axis by a master cam or form shaped in accordance with the work contour to be produced. The cam for controlling the truing tool movement is rotated in angular synchronism with the wheel. If a long piece of work is to be ground, the work and the grinding wheel may be axially reciprocated relative to each other by any standard reciprocating mechanism so that the wheel may be traversed throughout the length of the work while the irregularly shaped non-cylindrical surface of the grinding wheel and the work remain in operative contact, as is common practice in cylindrical grinding. A suitable cross feed mechanism may be employed to feed the grinding wheel towards the work as it wears away and to reduce the work to a predetermined size. It is to be understood, however, that the work and wheel axes are substantially immovable and they are not oscillated towards and from each other during the grinding operation. Hence, the only movement of these substantially fixed axes is the small relative feeding movement between the wheel and the work required to reduce the work in size.

40 One embodiment of my invention, as illustrated in the drawings, comprises a machine base carrying a grinding wheel 11 mounted on a rotatable spindle 12 which in turn is supported on a wheel slide 13. The work blank 15, which is a special type of splined shaft or integral key shaft covered by my co-pending application, Serial 215,983, filed August 27, 1927, is rotatably mounted between a headstock 16 and footstock 17 which are in turn supported on the work table 18. The axes of the grinding wheel and the work are fixed relative to each other during the grinding operation except for the relative feeding of the work and grinding wheel to reduce the work to the required size.

55 As illustrated in the drawings, a cross feed mechanism is provided to move the wheel slide and grinding wheel towards and from the work to reduce the same to a predetermined size. This mechanism may be of any suitable construction such as that shown in the patent to Wilcox No. 1,197,700 of September 12, 1916, to which reference may be had for a detailed disclosure thereof. This wheel feeding mechanism comprising a half nut 20 mounted on the underside of the wheel slide 13 and adapted to engage the feed screw 21 which is rotatably mounted in suitable bearings in a base 22. The outer end of the feed screw is provided with a gear 23 engaging a pinion 24 which is operatively connected to a hand wheel 25. By turning the hand wheel 25 a rotary movement is transmitted through gears 24 and 23 to screw 21 which, operating through the half nut 20, moves the grinding wheel slide and thereby causes a relative feeding movement between the

grinding wheel and the work. This feeding movement is utilized only to compensate for wheel wear or to feed the wheel to reduce the work to the required dimension.

It is essential that the rotation or the grinding wheel and the work be angularly synchronized so that the specially shaped operating face of the grinding wheel will produce a conjugate surface on the work.

To rotate these parts, a motor 27 is mounted either adjacent to the machine as shown in Fig. 1 or on or within the base 22. This motor drives a cross shaft 28 by means of a belt 29 passing over the motor pulley 30 and over the wide driven pulley or drum 31 fixed on the outer end of shaft 28 which serves to impart a synchronous rotation to the wheel and work. The shaft 28 is mounted in suitable bearings 32 and 33 on the wheel slide 13 and held in position by collar 34 and worm 35 engaging the ends of the bearings, whereby it is arranged for endwise movement with the wheel slide during the wheel feeding movement. The worm 35 is fixedly mounted on the shaft 28 and meshes with a worm gear 36 on the grinding wheel spindle 12. The other end of shaft 28 is provided with a worm 38 slidably fastened thereon by means of a key 39 and maintained in fixed driving relation with a worm gear 40 on the work driving spindle 41 which is mounted in the headstock. A yoked bearing support comprising spaced bearings 42 rotatably engaging shaft 28 and mounted on opposite sides of the worm 38, together with a head 43 connected by arms 44 to the bearings 42 is rotatably suspended from the work driving spindle 41. This construction serves to permit the grinding wheel to be moved towards and from the work without changing the angular relation of the wheel and the work, since the forward or rearward axial movement of shaft 28 is not imparted to worm 38 slidably keyed to the drive shaft 28. It will be readily seen from this construction that any rotation of the shaft 28 will be transmitted to rotate the grinding wheel and the work in synchronism.

As illustrated in the drawings, I have provided a triple worm 35 to engage the worm wheel 36 on the grinding wheel spindle 12 while on the other end of the shaft 28 the worm 38 is of the single thread type. By utilizing this arrangement, the grinding wheel will be rotated three times for each rotation of the work with the wheel and work both rotated in the same angular direction as shown in Fig. 6. This ratio of rotation of the grinding wheel and work is applicable only for grinding a body such as the cam illustrated in the drawings, in which the three lobes of the cam are symmetrical. In the case of the ordinary camshaft, such as used in internal combustion engines, it is necessary to employ a 1 to 1 ratio, wherein both the wheel and the work are rotated synchronously at the same angular rate. If desired, the wheel and the work may be rotated in opposite angular directions, so that their adjacent faces at point of grinding contact will travel in the same direction, although at different speeds.

A special feature of my machine involves a mechanism for truing the face of the grinding wheel to an irregular shape so that it will grind to produce the required conjugate work shape. As illustrated in the drawings, a truing apparatus 45 mounted on the wheel slide is adapted to support a truing tool such as a diamond 46 in operative relation with the face of the grinding wheel. The diamond 46 is mounted in the lower end of a

holder 47 which is slidably mounted in a vertical slide 48, as shown in Fig. 4. To shape the face of the grinding wheel so that it will produce a conjugate surface on the work of the desired size and shape, a master form or cam 49 is rotatably mounted on the slide 48 as illustrated. The rotation of the master form 49 will be transmitted to cause a movement of the truing tool 46 toward and from the surface of the grinding wheel. A spring pressed plunger 50 actuated by a spring 51 is provided to maintain the follower 52 in operative engagement with the master cam 49. A stud 53 threaded into the slide member 48 rides in a slot in the holder 47 and serves to prevent angular movement of the diamond holder.

It is essential that the master cam 49 be rotated in angular synchronism with the work spindle. As illustrated in the drawings, a spiral gear 54 is fixed on the work driving spindle and meshes with a spiral gear 55 on the lower end of a shaft 56 which is provided with a suitable bearing 57 secured on the headstock 16 by arm 58. A telescopic shaft 59 is connected with shafts 56 and 60 through universal joints 62 which permit the shafts to be out of alignment as the diamond is traversed across the face of the wheel and fed into the wheel as it is reduced in size. The shaft 60 is supported in a bearing 63 fixed on the slide 48 and has at its upper end a spiral gear 65 meshing with a spiral gear 67 secured on the end of the master cam shaft 68.

It will thus be seen that any rotation of the headstock spindle 41 will be transmitted to produce a corresponding rotation of the master form 49 which in turn transmits a movement to the diamond or truing tool 46 towards or from the periphery of the grinding wheel, thereby producing a surface on the grinding wheel which is the conjugate of the master cam. In the present instance, the master cam 49 as shown in the drawings is of identical size and shape as the final required work size and is, therefore, rotated in synchronism with the work piece 15 at the same angular rate. It is to be understood that other shapes of master cams and other constructional arrangements may be employed, but the master cam must be rotated in synchronism with the work spindle and it must be of such form as to cause the truing tool to shape the grinding wheel the exact conjugate of the final desired work shape.

In order that the diamond may be fed towards the periphery of the wheel as the wheel wears away, the truing tool is mounted on a vertical slide 48 which is slidably mounted on a horizontal slide member 70, so that the tool may be moved vertically towards and from the periphery of the wheel. As illustrated in the drawings, a nut and screw mechanism is provided to produce the desired adjustment of the vertical slide. This preferably comprises a screw 71 rotatably fixed in a suitable bearing 72 in the member 70 and threaded into a projection 74 of the vertical slide 48. The upper end of screw 71 is fixed to a hand wheel 75 so that it may be readily turned to position the truing tool 46 relative to the periphery of the wheel.

In order that the truing tool 46 may be traversed across the face of the wheel, any suitable mechanism may be provided, such as a cross slide 77 adapted to mate with a dove tailed sliding surface on the member 70 and positioned so that the sliding movement is parallel with the grinding wheel axis. A screw 80 is mounted in suitable bearings (not shown) in the cross slide 77 of the

truing mechanism engaging a nut or suitable projection 81 of the member 70 so that any rotation of the screw 80 will be transmitted to traverse the truing tool 46 across the face of the grinding wheel parallel to its axis. The screw 80 is provided with a hand wheel 82 so that the screw may be readily turned to produce the desired traversing action of the truing tool across the work.

As illustrated in Fig. 5, a modification of this invention has been illustrated whereby the wheel spindle 12' suitably mounted on the slide 13' may carry a plurality of grinding wheels 11' in spaced relation and arranged thereon to correspond with the positioning of cam blanks 15' on an automotive camshaft or the like. By employing a construction of this type, a plurality of cams or irregularly shaped objects on the same shaft may be simultaneously ground. The various constructional features on a machine utilizing more than one wheel are in general the same as above described, but will be duplicated as required for the grinding operation and for truing each wheel. The camshaft to be ground is rotated through the work drive spindle 41 and synchronized with the wheels by means of the drive shaft 28, which connects them as above described. Likewise the gear 54 driven with the work serves to rotate the shaft 56 and thus rotate the master camshaft 68 in synchronism with the work and the wheels, whereby the latter may be properly trued. It will be readily seen from this construction that the grinding wheels will not only be formed as the conjugates of the respective cams on a shaft, but they will be trued so as to produce the correct grinding of the various cams on the work piece 100 to be finished irrespective of the shapes and the angular positions of each cam on the shaft.

In the operation of my machine a master form or cam of the required shape is mounted in operative relation with the truing mechanism. The grinding wheel of suitable characteristics is then set in rotation and the hand wheel 75 is turned to feed the diamond truing tool 46 into operative relation with the face of the grinding wheel 11. The hand wheel 82 is then turned to traverse the diamond across the face of the wheel after which the hand wheel 75 is turned to produce a further feeding of the diamond into the face of the wheel. This operation is continued until the grinding wheel has been trued so that its shape is the conjugate of the master form or template, thereby forming the grinding wheel as the conjugate of the required work shape. During the truing operation, the rotation of the grinding wheel and the master cam 49 in angular synchronism causes the truing tool 46 to move towards and from the wheel axis in a definite phase relation with the wheel rotation in order to true the wheel face to the desired contour. The work blank is then mounted on centers between the headstock 16 and 135 footstock 17. After the work and wheel have been angularly located and put into synchronous rotation, the grinding wheel is fed forward by turning the hand wheel 25, which in turn serves to rotate the feed screw 21, thereby transmitting a feeding movement to the slide 13. The work blank will be rotated in synchronism with the grinding wheel so that any high spot on the wheel will produce correspondingly low spots on the work and vice versa as shown diagrammatically in Fig. 6. The grinding operation continues as the operator feeds the wheel into the work until the work blank has been ground to a predetermined shape and size which is the conjugate of the peripheral surface of the grinding wheel.

It is to be understood that the term "conjugate" as used in this specification and in the claims is associated with those curves which are so related as to be produced by the rotation of the connecting surfaces of the tool and the work about fixed axes with their angular velocities equal or in a simple ratio, where these surfaces are in part irregular in shape and their peripheries are of unequal extent. If the work and the wheel were rotated in opposite directions and their circumferences were the same in length and their angular velocities were the same, the two surfaces would have a pure rolling contact; but with the dissimilarity of length of the two peripheries a slipping or cutting action between the wheel and the work serves to grind the latter to size. If the wheel and the work rotate in the same direction, the cutting conditions are the same as in a normal cylindrical grinding operation. They may be rotated in opposite directions, if desired. It is essential, however, that the work and the grinding wheel rotate in fixed angular synchronism and that the wheel be so shaped that for each revolution thereof it will reproduce a conjugate shape on the work.

It is to be understood that the present invention applies to forming eccentrically revolved cylindrical surfaces, such as crank pins, as well as non-circular peripheral surfaces, the cross section or contour of which do not form geometric circles, such as cams, and to the forming of irregular surface contours on the side faces of rotary bodies. In each case, the line of grinding contact between the wheel and work is at a varying distance from the axis of rotation of the grinding wheel, or in other words the line of grinding contact moves towards and from the axis of wheel rotation during the grinding operation. For example, a wheel employed for grinding a crankpin may be circular in shape but eccentrically mounted relative to its geometric center. The work and the wheel are said to be in "angular synchronism" when their angular velocities are in simple ratios of one to one, two to one, three to one and so forth. Similarly, the master form and the truing tool move in cyclic synchronism or phase relation with each rotation of the wheel, in that the master form or the tool moves always in the same definite path for each rotation of the wheel through the same angular distance, and the cycle is repeated either once or a multiple number of times for each full rotation of the wheel. In other words, wheel and work are always rotated through a proportionate angular displacement.

This application of conjugate grinding or forming of a work piece has been illustrated as applicable to grinding the outer surface of a body, but this invention is not limited to this application. It is equally applicable to grinding holes of an irregular shape by forming the grinding wheel so that when it rotates in synchronism with the work blank, it will produce a conjugate surface on the inner periphery of the work aperture. These principles apply to various types of grinding machines, in which the wheel grinds on its peripheral or on its side face, and they apply also to the production of many different shapes of work. Various other applications of this invention are clearly within the scope of the appended claims.

Having thus described the invention, what is claimed as new and desired to secure by Letters Patent is:

1. A grinding machine comprising a grinding wheel, a truing tool movable laterally and to-

ward and from the wheel, means to traverse the truing tool across the operative face of the wheel, a rotary master form connected to move the truing tool towards and from the wheel face and means to rotate the master form in synchronism with the grinding wheel so that the conjugate of the master form will be produced on the grinding wheel.

2. A truing apparatus for grinding machines comprising a wheel slide, a grinding wheel thereon, a truing tool holder mounted on said slide for movement laterally thereof and towards and from the wheel, means to traverse said tool across the face of the wheel, a rotatable master form connected to move the truing tool towards and from the grinding wheel and means to synchronize the rotation of the grinding wheel and the master form so that the conjugate of the form will be generated on the grinding wheel.

3. A wheel truing mechanism for operation on a surface of a rotating wheel including a support, a truing member mounted on the support for movement in a direction transversely of the wheel surface to be formed and for movement in a direction toward and from the surface to be formed, means for effecting a traversing movement of the truing mechanism with respect to said surface, and additional means for automatically effecting a cyclic movement of the truing mechanism toward and from said surface for each rotation thereof.

4. A mechanism for producing an eccentric surface on the periphery of a rotatable wheel including a support in fixed relation to the axis of rotation of the wheel, a truing member mounted on the support for movement in a direction toward and from the periphery of the wheel, a contour determining member rotatable in synchronism with the wheel, and connections between the truing device and contour member determining the movement of the truing member toward and from the periphery of the wheel on joint rotation of the wheel and contour member.

5. A mechanism for producing an eccentric surface on the periphery of a rotatable wheel including a support in fixed relation to the axis of rotation of the wheel, a truing member mounted on the support for movement in a direction toward and from the periphery of the wheel, a contour determining member rotatable in synchronism with the wheel, connections between the truing device and contour member determining the movement of the truing member toward and from the periphery of the wheel on joint rotation of the wheel and contour member, and means for effecting a relative transverse shifting movement of the wheel and truing member in a direction axially of the wheel, whereby the truing member will engage all points of the desired zone transversely of the wheel in a relation to the axis thereof determined by the means for controlling the movement of the truing member toward and from the wheel surface.

6. A mechanism for producing an eccentric surface on the periphery of a rotatable wheel including a support in fixed relation to the axis of rotation of the wheel, a truing member mounted on the support for movement in a direction towards and from the periphery of the wheel, a contour determining member rotatable in synchronism with the wheel, connections between the truing device and contour member determining the movement of the truing member towards and from the periphery of the wheel on joint rotation of the wheel and contour member, means for

- effecting a relative transverse shifting movement of the wheel and truing member in a direction axially of the wheel, whereby the truing member will engage all points of the desired zone transversely on the wheel in a relation to the axis thereof determined by the means for controlling the movement of the truing member towards and from the wheel surface, and additional means for effecting a manual adjustment of the truing member in a direction towards and from the wheel surface. 5
7. A grinding machine having a base, a rotatable grinding wheel of non-circular contour mounted thereon, a truing apparatus having a tool arranged to move towards and from the wheel axis and to traverse across the face of the wheel, and a master form rotated in synchronism with the wheel which is connected to actuate the truing tool and produce a wheel face shaped as the conjugate of the master form. 10
8. A grinding machine comprising a grinding wheel of a non-circular contour adapted to grind a conjugate non-circular work shape, a truing tool, a support for moving the tool towards and from the wheel axis to true said wheel contour, a master form connected to control the truing movement of the tool which has a predetermined contour related to that of the finished work and means for moving the master form in cyclic synchronism with each grinding wheel rotation during the truing operation, whereby the wheel is trued to a contour of non-circular section which is the conjugate of the finished work shape. 15
9. A grinding machine, having a base, an axially fixed rotatable grinding wheel having a cutting face shaped to a contour which is conjugate to the desired shape of the finished work, means to rotate the wheel and work in abrading engagement on substantially fixed axes and in angular synchronism to produce the desired work shape, and truing mechanism, including a truing tool and means for moving the tool which is operated in synchronism with the work rotation for shaping the wheel face to be the conjugate 20 of the desired work shape.
10. A machine adapted for grinding a surface of irregular contour comprising a grinding wheel having a contour which is the conjugate of that of the finished work, and a rotatable work support, means to rotate the work and wheel in angular synchronism while their surfaces are in engagement and their axes are in a non-oscillative relation to produce the desired work shape, and a truing mechanism, including a master cam 25 rotated in synchronism with the work rotation, for shaping the wheel periphery as the conjugate of the desired work contour.
11. A grinding machine comprising a grinding wheel having its line of contact with the work piece at a varying distance from the axis of wheel rotation, a tool support, a truing member mounted on the support for movement towards and from the wheel axis, and means for effecting a movement of the truing member towards and from said wheel axis in cyclic phase relation to each wheel rotation so as to true said wheel face to the desired contour. 30
12. A grinding machine comprising a grinding wheel having its line of contact with the work piece at a varying distance from the axis of wheel rotation, a tool support, a truing member mounted on the support for movement transversely of the wheel periphery and for movement towards and from the wheel axis, means for effecting a transverse movement of the truing member with respect to the wheel periphery, and means for effecting a movement of the truing member towards and from said wheel axis in cyclic phase relation to each wheel rotation so as to true said wheel face to the desired contour. 35
13. A grinding machine comprising a grinding wheel having the line of grinding contact at a varying distance from its axis of rotation, a truing tool, a support for the tool including a rotatable master form arranged to move the tool towards and from the wheel, and means to rotate the master form and grinding wheel in angular synchronism about stationary axes so as to move the truing tool cyclically towards and from the grinding wheel and thereby shape the wheel periphery to a predetermined contour. 40
14. A grinding machine comprising a wheel slide, a grinding wheel thereon having its line of grinding contact at a varying distance from the axis of wheel rotation, a truing tool holder mounted on said slide for movement laterally thereof and towards and from the grinding wheel, means to traverse the tool across the face of the wheel, means including a rotatable master form having a curved operative face which is at a varying distance from its axis of rotation and arranged to cyclically move the truing tool towards and from the grinding wheel during each wheel rotation, and means to synchronize the rotation of the grinding wheel and the master form so that the wheel will be shaped to a predetermined contour. 45
15. A grinding machine comprising a grinding wheel, having its line of grinding contact at a varying distance from the axis of wheel rotation, a support mounted in fixed relation to the axis of rotation of the grinding wheel, a truing tool mounted on the support for movement in a direction towards and from the wheel axis, a master form rotatable in angular cyclic synchronism with the grinding wheel, connections between the truing tool and master form determining the movement of the truing tool towards and from the wheel axis, and means to feed the master form towards the wheel axis and compensate for wheel wear without affecting its angular relation therewith, whereby the truing tool may be maintained in engagement with the grinding wheel as it is reduced in size and serve to shape it to a predetermined contour. 50
16. A grinding machine comprising a grinding wheel having its line of grinding contact at a varying distance from the axis of wheel rotation, a truing tool therefor, means for traversing the tool transversely across the wheel face, mechanism including a rotatable master form to move the truing tool towards and from the wheel axis during the truing operation, positive driving connections between the wheel and master form arranged to rotate the master form in cyclic synchronism with the wheel rotation whereby the truing tool may be caused to move in timed relation to the wheel rotation and shape the grinding wheel to a predetermined contour, and means to feed the master form towards the grinding wheel to compensate for reduction in wheel size without disturbing the synchronism of the master form and grinding wheel. 55

EVERARD STUBBS.
